UNITED STATES PATENT OFFICE.

NORMAN P. HARSHBERGER, OF CHICAGO, ILLINOIS, ASSIGNOR TO TEE-LOK SHINGLE COMPANY, OF CHICAGO, ILLINOIS, A CORPORATION OF ILLINOIS.

SHINGLE.

1,410,299.

Specification of Letters Patent. Patented Mar. 21, 1922.

Application filed September 30, 1920. Serial No. 413,836.

To all whom it may concern:

Be it known that I, NORMAN P. HARSHBERGER, a citizen of the United States, residing at Chicago, in the county of Cook and State of Illinois, have invented certain new and useful Improvements in Shingles, of which the following is a specification.

This invention relates to shingles for covering roofs, and has for its object the production of suitable shingles for the purpose which may be readily placed on the roof so as to present a very pleasing appearance and to prevent any leakage and at the same time to require a minimum amount of lapping of the shingles, and hence to reduce to a minimum the amount of material necessary to cover the roof.

Of the drawings Fig. 1 is a plan view of a portion of a roof covered by my shingles; Fig. 2 is an under view of one strip of shingle material; Fig. 3 is a top view of another strip of material; Fig. 4 is an enlarged section along the line 4—4 of Fig. 3; Fig. 5 is another enlarged section along the line 5—5 of Fig. 2; Fig. 6 is a materially enlarged section along line 6—6 of Fig. 1; and Fig. 7 is a sectional view showing how the ends of similar strips are connected.

The shingles comprise a plurality of units connected in strips. While modifications may be made in the number of units in a strip and in the shape and dimensions of the units and strips, yet I prefer the strips 10 and 11 composed of units 12 and 13 respectively. The strips 11, a plan view of which is shown in Fig. 3 are the lower strips, and have folded portions 14 spaced a material distance apart so as to form the unit portions 13, and when placed on the roof the edges 15 of the folded portions are placed upwardly and at the lower edge of the unit and thus gives the appearance of the ordinary double butt shingle; and the strips, ordinarily comprising 4 or 5 units, are connected together as indicated at the joint 16 of Fig. 7; the arrangement being such that it is impossible for the rain to work through at the joint. The strips 11 have cemented to their edges narrow strips 17 which prevent the rain working in over the edges of the strips.

In laying the roof the strips 11 are first placed upon the roof boards, suitably spaced apart, and are nailed to the roof boards

along the edges of the strips, for example, 55 at the points 18. The spaces between the strips 11 are covered by the upper strips 10 which lap a material distance on the strips 11 at least sufficiently to somewhat more than cover the strips 17. The strips 10 also 60 have folds 20 similar to the folds 14, and at the ends may be connected similarly to the connection 16 of Fig. 7. Fig. 2 shows the underside of one of the strips 10, with blocks 21, of any suitable material, cemented 65 to the lower side of the edges of the strips. These blocks have projecting fingers 22 which, when the strips 10 are placed on the roof, are slipped under the upper portion of the fold 14, Fig. 6, the blocks 21 coming 70 on the strips 11 inside of the strips 17. In this manner the strips 10 are held firmly to the roof by means of the strips 11, and it is necessary to nail down the strips 10 only sufficiently to prevent them from sliding 75 downwardly on the roof. These nails may be placed where convenient, for instance at the upper ends under the ridge strips.

Obviously the width of the strips 10 and 11 may be made whatever may be desired for 80 appearance or use; the distance between the folds 14 or 20 may be varied, and the amount of lapping of the strips may also be varied as much as desired, so as to vary the 85 appearance or the amount of material used, or the amount of protection from weather, according to the desires of the builder.

I claim as my invention:

1. A roof covering comprising substantially parallel strips of roofing sheets fixed 90 to the roof and spaced a material distance apart; other strips of roofing sheets placed on the roof covering the spaces between the first mentioned strips, and lapping thereon; all of the strips having transverse folds 95 spaced a material distance apart, the folds in the first mentioned strips being aligned, but being staggered with the folds of the other strips which are also aligned; a narrow strip fixed to the upper side of each edge 100 of each of the first mentioned strips; and blocks fixed to the lower side of each of the other strips, each of said blocks having a finger projecting upwardly and under the adjacent fold of one of the first mentioned 105 strips.

2. A roof covering comprising lower strips of roofing material running down the roof

- and spaced a material distance apart, upper strips running down the roof between the lower strips and lapping thereon, each of the lower strips having a plurality of transverse folds, each of the upper strips having fixed to its lower side a plurality of fingers, each of the fingers, when the strips are laid, being adapted to pass under one of the folds in the adjacent lower strip.
- 10 3. A roof covering comprising substantially parallel strips of roofing sheets fixed to the roof and spaced a material distance apart; other strips of roofing sheets placed on the roof covering the spaces between the first mentioned strips, and lapping thereon; all of the strips having transverse folds spaced a material distance apart, the folds in the first mentioned strips being aligned, but being staggered with the folds of the other strips which are also aligned; and means fixed to the lower side of each of the other strips and passing under the adjacent fold of one of the first mentioned strips.
4. A roof covering comprising two layers of strips of roofing material running down the roof, substantially parallel with each other, the strips in each layer being spaced apart, and the strips of the upper layer covering the spaces between the lower strips, each of the strips having transverse folds therein, the folds of the lower strips being aligned but being staggered with the folds of the upper strips.
5. A roof covering, comprising a plurality of laterally spaced top and bottom strips with the top strips extending over the spaces between the bottom strips and overlapping the same along their side edges, each strip consisting of one continuous piece of roofing material, and being folded transversely upon itself at a plurality of spaced points in its length to provide a multiple thickness of material at each of such points to give the top surface of the strip a step-shaped appearance; the folds in the bottom strips being out of alignment with the folds in the top strips to give the roof covering a shingled appearance.
6. A roof covering, comprising a plurality of laterally spaced top and bottom strips with the top strips extending over the spaces between the bottom strips and overlapping the same along their side edges, each strip consisting of one continuous piece of roofing material, and being folded transversely upon itself at a plurality of spaced points in its length to provide a multiple thickness of material at each of such points to give the top surface of the strip a step-shaped appearance; the folds in the bottom strips being out of alignment with the folds in the top strips to give the roof covering a shingled appearance, and means carried by the top strips on the under sides thereof to engage in the folds in the bottom strips for holding the strips together.
7. An article of manufacture comprising a strip of sheet roofing adapted to be laid transversely on a roof and having a plurality of equally spaced transverse closed double folds, one end of each of said strips having a transverse single fold adapted to coact with a similar fold of another strip so as to increase the effective length of the strips, and narrow strips fixed to each longitudinal edge of each of said strips.
8. A roof covering, comprising two layers of strips of roofing material running down the roof, the strips in each layer being spaced apart a material distance and the strips of the upper layer covering the spaces between the lower strips, each of the strips having transverse double folds, the folds in the respective layers being aligned, but being staggered with the folds of the strips of the other layer, and a strip of material fixed to the upper side of each edge of each of the lower strips and extending the entire length of said strip.
- In testimony whereof, I hereunto set my hand.
- NORMAN P. HARSHBERGER.
